MACHINE FOR HIGH SPEED, EXTREMELY PRECISE MASS WORKING OF PIECES HAVING SMALL DIMENSIONS AND COMPLEX FORMS, IN PARTICULAR OF METALLIC SMALL ARTICLES

The present invention relates to a machine for the high speed, mass production with extreme precision of small pieces with complex forms such as: electric contacts, screws, horological pieces, carburetor nozzles, breaker contacts, special pieces for cameras and delicate equipment or apparatuses and in general metallic small articles.

There exist at present several automatic machines for the rapid manufacturing of metallic small articles such as ball point pens, screws and the like (see for instance the Swiss Patent Nos. 337,053 and 358,003). These machines are however expressly designed and constructed to manufacture a single type of article, for instance either ball point pens or electric plugs or screws so that, should it be wanted to manufacture with a given machine an article that is different from the one the machine is designed for, it would be necessary to change a great many parts of said machine.

The machine according to the present invention, on the contrary, without requiring substantial changes of production accessories, may be rapidly adapted to produce with very high precision (tolerance of the order of the microns) articles of very small dimensions and complicated forms which are different one from the other. Furthermore, the machine of the invention is so devised as to make it possible to change, with great rapidity and within a wide range, the working speed while maintaining constant the speed at which the articles are fed from one working-station to the next one. This feature is responsible for a considerable increase in the production and, as a consequence thereof, for a considerable reduction of the cost of the finished articles.

In particular the machine of the present invention is characterized:

by a turntable stepwise rotating about a central shaft and provided with a plurality of discs carrying the workpieces, said discs being distributed at equally spaced angular intervals along the periphery of said turntable, each interval corresponding to a station in which a certain work operation is carried out, the different work operation being effected simultaneously on different workpieces; coaxially and externally to said central shaft there being disposed in succession from the inside to the outside: an inner stationary sleeve, an intermediate bush rotating with said turntable and an outer stationary frame;

by main members which intermittently move said turntable to pass from one working station to the next one in the shortest possible time;

by tool-holding chucks situated in each working station and disposed above, at the side of and under the periphery of said turntable in correspondence to each workpiece, said chucks having their working movement imparted thereto by groups of peripheral cams (i.e. disposed at the periphery of the turntable between one station and the next) as well as by a group of axial cams (i.e. disposed along the axis of the turntable) with possibility of simultaneously operating on the pieces with at least three chucks for each workpiece-carrying disc, said chucks having their axes differently disposed and orientable as a whole over an angle of about 200°

and being fixable to the outer stationary frame coaxial to the central shaft;

by means which exactly fix with great rigidity the position reached by the turntable at each working station before starting the work operation, said fixing being obtained by engaging and firmly holding said stationary inner sleeve as well as said external stationary frame;

10 by secondary members which displace angularly to itself the axis of each workpiece-carrying disc so as to bring the same into the right working position and means to fix the same in exact position before starting the working process; said discs being so shaped as to permit working with chucks placed below and above same.

The accompanying drawings show a preferred non-limitative embodiment of the machine according to the present invention.

20 FIG. 1 is a diagrammatic axially sectioned view of said machine.

FIG. 2 is a cross-sectional view of FIG. 1 taken along the plane passing through AB to illustrate the details of the members controlling the stepwise movement of the turntable carrying the pieces to be worked on.

25 FIGS. 3, 4 and 5 are detailed axially sectioned views of the same members.

FIGS. 6, 7, 8, 9, 10, 11 are views of details of the damping devices for the means driving the turntable as 30 well as of the tappets and of the tie rods.

FIGS. 12 and 13 are details of the device for rotating the discs carrying the grippers holding the workpieces, said discs being distributed at the periphery of the turntable.

35 FIG. 14 is a plan view of the device actuating the main shaft.

FIGS. 15 and 16 are views of an actuating device for the turntable with a direct current motor, the speed of which is electronically controlled.

40 FIGS. 17 and 18 are views of a mechanical device to increase the displacement speed of the turntable.

FIGS. 19, 20, 21 are views of a rocker arm device for the feeding motion of the tool-carrying chucks.

45 FIGS. 22 and 23 are views of a displacement system for the axes of the chucks parallel to themselves, said system being called "working center with stationary coordinates" (also applicable to each chuck).

FIG. 24 is a view of a device applicable to each 50 chuck for the displacement thereof along two coordinate axes, a vertical and a horizontal one.

FIGS. 25, 26, 27 are views of a device enabling the tool of the chuck, to which it is applied, to effect circular motions.

FIG. 28 is a view of a rotating device feeding and straightening the raw wire fed to the machine for obtaining the various finished articles.

FIGS. 29 and 30 are views of a roller device for feeding and straightening the raw wire horizontally inserted in the self-centering grippers.

60 FIGS. 31 and 32 are views of a device to charge the corresponding self-centering grippers with pressed, stamped, pre-turned or in any other way pre-shaped rough pieces or blanks.

With reference to the various figures: the main motor 65 3 (FIG. 1) situated in the base frame 1 drives, by means of a belt speed-varier, the worm wheel 4 and therewith the main shaft 5.

This shaft actuates in its turn, through the toothed wheels 6 and the bevel gears 7, the groups of lateral cams 8 situated outside of each lateral surface of the hexagonal casing 2 (see FIGS. 2 and 14). Thus there are six groups of cams 8 distributed in correspondence to each lateral surface of the hexagonal casing.

Coaxially to the central shaft 5 and externally thereto there are disposed in succession from the inside to the outside:

the stationary inner sleeve 194 (fixed with the base frame 1), the intermediate rotating bush 18 and the outer stationary frame 193. This particular disposition has considerable advantages which will be illustrated later on.

The stepwise rotating turntable 16 is fixed to the intermediate rotating bush 18 and is intermittently operated by the secondary turntable 9 illustrated in FIG. 2, in the following manner:

The first cam 19 which is provided in the secondary turntable 9 actuates by means of the roller 20 and the levers 21, 22, 23 the central oscillating lever 24 (see also FIG. 1) which is mounted idle on the central shaft 5 so as to impart to said oscillating lever an oscillatory accelerated and decelerated motion, the amplitude of which corresponds to the angular displacement which is to be imparted to the stepwise rotating turntable 16.

Noteworthy is the detail of the connection between the levers 22 and 23 which takes place over a "click-joint" (FIGS. 4, 5) in the following manner: the lever 23 (FIGS. 2, 3) carries at its end a fork member 23' having the slide 191 (FIG. 5) sliding therein. Said slide 191 is pivoted on the lever 22 (FIG. 2) and is connected to the bush 193 (FIG. 4) by means of the rod 192. The body 195 (FIG. 4) fixed to the fork member 23' (FIG. 5) of the lever 23, is resiliently connected to the bush 193 through the balls 194' situated in the holes provided in the above mentioned body 195. The balls 194' are pushed by the sleeve 190 and by the spring 196 into the groove 193' of the bush 193. During the normal operation of the machine the joint acts as a rigid connection member. In the event of a jamming up of the machine, i.e. in case the force required to displace the rotating turntable 16 should exceed the normal value, the component of the forces acting through the balls 194' between the bush 193 and the sleeve 190 would overcome the counterforce of the spring 196; the bush 193 would then move with respect to the body 195 so that the balls would leave the groove 193'. As a consequence thereof the force would then practically fall to zero so as to prevent any damage to the mechanical parts. During this operation, the sleeve 190 displaces the block 200 and disconnects the switch 201 which, in its turn, acts on the emergency brake. By means of the threaded nut 197 it is possible to exactly set the oscillating lever 24 (FIG. 3) so that the piston 25 is positioned with great precision with respect to the complementary pins 18' protruding from the intermediate bush 18 as it will be better explained later on. The damping device 198 (FIG. 2) is provided for damping the whole system.

Going back again to FIG. 3: the lever 24 carries the small piston 25 which is vertically displaced by the double acting cam 26.

By moving upwards, the small piston 25 enters with its conical opening 25' into one of the complementary pins 18' protruding from the intermediate rotating bush

18. The double acting cam 26 lifts the small piston 25 in the forward moving phase of the oscillating lever 24 and therefore of the stepwise rotating turntable 16 and lowers the same in the return phase of the oscillating lever 24.

To increase the operational security of the machine, the small piston 25 actuated by the double acting cam 26 is provided with a damping device. Said damping device comprises a cylindrical body 45 (FIGS. 6, 7, 8) pushed upwards by the springs 49 which act on the body itself through the small plate 47 and the balls 48 (see the detailed construction in FIG. 7).

During the normal operation of the machine, the cylindrical body 45 enters into the conical pins 18' of the sleeve 18 (see FIGS. 1, 3, 6) and, to obtain a perfect tightness without any clearance, said cylindrical body 45 must resiliently adapt itself to the associated pin.

20 The cam 26 imparts to the cylindrical body 45 a stroke some tenths of a mm. larger than normal so that the springs 49 also are compressed thereby some tenths of a millimeter.

In case of accidental phase displacement of the machine, the cylindrical body 45 undergoes an elastic yielding along the whole length of its projecting part, without however exerting a force great enough to be harmful to the machine.

25 In this case, once a certain relative displacement or travel between the cylindrical body 45 and the container 46-46' has been exceeded, the balls are pushed towards the periphery of the container 46-46' while the vertical force on the cylindrical body 45 decreases.

30 A further advantage consists in that the displacement of the small plate 47 and of the springs 49 is less than half of the displacement of the cylindrical body 45.

The small plate 47 has fixed thereto a pin 47', which actuates in case of accidental phase displacement the lever 50 which, in its turn, controls the electric contact 51 by means of the magnet 85. The contact 51 activates the emergency brake.

During operation the rotating turntable 16 is made stationary by the rods 14.

To prevent any breakage of machine elements in case of incorrect functioning or blockage of the machine, the tappets controlling the work stations are provided with release damping devices as illustrated in FIGS. 9 and 10, comprising a hollow cylinder 41 and a coaxial stem 42; the balls 40 are pressed in the groove 42' by the sleeve 44 and by the spring 43. The stem 42 stays thus positioned with respect to the hollow cylinder 41. Hence, under the normal working stress 55 the tappet behaves like a rigid body. Under a stress larger than normal, on the contrary, the balls move outwards displacing the ring 44 and compressing the spring 43. The stem 42 remains therefore free to slide in its axial direction practically without any strain.

60 The advantage of the device consists in that, once the maximum allowable stress has been exceeded, the axially acting force practically falls to zero.

With a conventional spring damping device, on the contrary, the stress would increase proportionally to the displacement.

FIG. 11 illustrates a tie-rod functioning on the same principle.

The rotating turntable 16 with its gripper-carrying discs 17 (FIGS. 12 and 13) is so designed and constructed as to permit the fixing of the working centers each comprising, for instance, up to three chucks with the associated independent electric motors which may be fixed vertically above as well as vertically below the turntable itself. However they may also be fixed horizontally or so as to form any angle comprised between 0° and 200°. The rotating turntable 16 is provided at its periphery with a plurality of holes to contain the gripper-holding discs 17.

Simultaneously with the displacement of the rotating turntable 16, said discs 17 may be rotated through a certain angle while passing from one working station to another.

To this end the toothed wheel 32 fixed below the gripper-carrying disc 17 engages during the rotation of the turntable 16 the toothed segment 33 fixed to the machine body, thereby imparting to the gripper-holding disc 17 a rotation through a certain angle.

Said angle depends on the number of teeth of the segment 33. By varying the number of teeth of the segment 33 is thus possible to vary said angle.

Obviously the segment 33 is fixed in the interval comprised between one working station and the next one only when it is required to rotate the work piece in the space between said stations. Hence the toothed wheel 32, after that rotation, must be free to move together with the rotating turntable 16 without rotating about itself. This is the reason why the last tooth 33' of the toothed segment 33 is so constructed as to be lower than the other teeth.

Furthermore, to facilitate the engagement of the toothed wheel 32 with the segment 33, the part "D" of the wheel 32 is not provided with the teeth which would precede the teeth 32' providing for the engagement with the toothed segment 33.

To ensure a perfect positioning, before starting the work operations, the gripper-carrying discs 17 are blocked relative to the rotating turntable 16 by means of the rods 15 (see also FIG. 1).

The rods serving to block the discs 17 and the rods 14 serving to block in the desired positions the rotating turntable 16 are controlled by the cam 10 fixed to the secondary turntable 9 fixed, in its turn, to the main shaft 5 (FIG. 1). The double acting (in both directions) cam 10 controls the disc 13 through the rollers 11 and the rods 12. Said disc has fixed thereto a certain number of said rods 14, 15 which, by moving upwards, fix or set the position of the rotating turntable 16 and of the gripper-carrying discs 17, as mentioned above.

A very important detail which constitutes one of the fundamental characteristics of the machine according to the present invention is constituted by the fact that rods 14 block very firmly and rigidly the rotating turntable 16 by passing through the outer stationary frame 193, through the inner stationary sleeve 194 as well as through the intermediate bush 18 rotating together with the turntable. To avoid any play, the rods 14 (and 15) move axially, penetrating into bushes provided with ball rings which are resiliently compressed by the rods.

The control of the working centers is effected by the already mentioned groups of cams 8 disposed at the side of the hexagonal frame and acting by means of tap-

pets, as well as by the groups of cams 95 fixed to the upper end of the central shaft (see FIG. 1).

With regard to this point it should be noted that the ratio of the gear pairs 6, 7 are so chosen that the shafts carrying the groups of cams 8 have a ratio 1/1 with respect to the central shaft 5 and furthermore so that the number of teeth of the central bevel gear 7 is a multiple of the number of cam groups so as to allow for a ready phase setting.

10 By means of the modified device illustrated in FIG. 14 it is possible to accelerate the displacements of the rotating turntable 16.

The main motor 3 (see also FIG. 1) actuates, through a speed varier, the shaft 27 which, in its turn, actuates the shaft with the helical gear 4, through the electromagnetic coupling 28.

The shaft 27 carrying the helical gear 4 is furthermore provided with an electromagnetic brake 29.

20 The shaft with the helical gear 4 has coupled to its other end, through a further electromagnetic coupling 30, another motor 31.

25 By connecting the coupling 28, the main shaft 5 is actuated by the main motor 3 while, by connecting the electromagnetic coupling 30, the shaft 5 is actuated by the motor 31.

The coupling 29 is connected to block the shaft 5 in case of emergency stopping.

30 It obviously appears that, by means of this device, the shaft 5 can rotate at two speeds: a first speed n_1 imparted by the motor 3 and variable by means of the varier, and a second speed n_2 imparted by the motor 31.

It is thus possible to vary the working time (i.e. the time during which the rotating platform 16 (FIG. 1) is made stationary and the working members effect the working operations) while maintaining constant (and minimal) the time for the displacement of the rotating platform from one position to the other.

40 The connection of the electromagnetic couplings is controlled by a contactor which in its turn is controlled by one of the cams 8.

According to another modification of the above mentioned device, use may be made of a single direct current motor with electronic speed control, as illustrated in FIGS. 15 and 16.

45 For passing from one speed n_1 to another speed n_2 it is necessary to commute the reference potentials, i.e. the potentials relative to the speeds, by means of electric or electronic contacts controlled by one of the cams 8.

50 The rapid change from one higher speed n_2 to a lower speed n_1 may be obtained by means of a dynamic braking process according to which the direct current motor acts as a generator until the speed n_1 has been reached.

55 The circuit is diagrammatically represented in FIG. 16. The motor 52 has a generator tachometer 53 coupled thereto which produces a potential which is directly proportional to the number of revolutions of the motor. The rotational speeds are preselected by means of the potentiometers 54, 55. A commutator 63, controlled by one of the cams 8, effects first one and then the other of the preselected speeds.

60 65 The electronic circuit 64 compares the potential of the tachometer with the potential of the inserted potentiometer and controls, as a function of said potentials,

the thyratron-transistors bridge 65 (the thyratron transistors function as electronic thyratron tubes).

To enable a rapid change from one high speed to a lower one, there is provided a braking circuit which operates in the following manner:

when a potentiometer 54 or 55 preselected for a lower speed is inserted, a detector in the circuit 64 turns on the thyratron-transistor 58 (in this case, obviously, the thyratron-transistors of the bridge 65 are turned off).

In this way the potential given by the electromotive force of the motor will cause a flow of current through the braking resistance 59. The motor 52 functions then as a generator.

Once the required rotary speed has been reached, the circuit 64 turns on the thyratron-transistor 86 which enables the discharge of the condenser 61. The potential of the condenser 61, which is higher than that given by the electromotive force of the motor, will cause the switching off of the thyratron-transistor 58.

The discharge of the condenser 61 occurs by way of the inductance 62 which makes it possible that said discharge takes place periodically and causes the self-switching-off of the thyratron-transistor 86.

The electromagnetic brake 87 is provided for emergency stopping in case of current failure.

When the machine is functioning, the brake is constantly under a voltage and the electromagnetic circuit of said brake compresses the springs 68.

In case of current failure, the springs 68 push the disc 69 against the motor shaft whereby the same is brought to a stop.

There is also provided a mechanical device contributing to the acceleration and deceleration, i.e. enabling one to increase the displacement speed of said rotating turntable 16 (FIGS. 17, 18).

This device is so constructed as to enable one to increase the displacement speed of the rotating turntable without subjecting the driving members of said turntable to further loads.

The inner stationary sleeve 194 is provided with radial holes adapted to receive the small pistons 101 pushed outwards by the springs 102.

The small pistons 101 have rollers 104 fixed thereto, which roll along the concave surfaces 105 of the intermediate bush 18 rotating together with the turntable 16.

When the rotating platform is stopped, the bush 18 is located in the position 103, i.e. the rollers 104 are positioned in the highest region of the concave surfaces 105 and as a consequence thereof the springs 102 are compressed.

When the turntable 16 starts to rotate, the expansion of the springs 102 imparts to the bush 18 a force in the sense of rotation of the bush itself until the rollers 104 have reached the lower point, i.e. the central part of the concave surfaces 105. From this moment on, the springs are compressed again and impart to the bush 18 a force in opposition to the direction of rotation.

It is obvious that the forces imparted by the springs 102 contribute to the acceleration and deceleration of the rotating turntable 16 and of the members fixed thereto, thereby to increase the displacement speed of the above mentioned turntable.

There will be described in the following a rocker arm device for the control of the displacement or travel of each tool-carrying chuck illustrated in FIGS. 19, 20, 21.

5 The tappets 66 (see also FIG. 1) act through the lever 117 (FIGS. 19, 20) on the pivot 118. This pivot transmits the movement to the levers 119 by means of the shaped pawl 70 and of the hexagonal bushes 71-71' (FIGS. 20, 21).

10 The pawl 70 is provided with two lateral recesses 70', 70'' (FIG. 21) which define a central projecting portion having the central driving force acting thereon so as to allow for a relative movement between the bushes 71, 71'. In other words, this combination of parts acts as a rocker arm device distributing in equal manner the forces on the levers 119 (the forces being indicated with arrows in FIG. 21).

15 In other words, the tappet 66 acts against the lever 117. The lever 117 through the key 200 rotates the pivot 118. The pivot 119 is integral with the collar 118' which has an upper groove 203 in which is inserted the pawl 70 and a lower groove in which is inserted another pawl 70. The hexagonal bushes 71, 71' integral with the lever 119 present two holes 201, 202 in which are engaged the ends of the pawl 70.

20 The chuck moves therefore always in perfect equilibrated position with respect to the workpiece.

25 To allow for the displacement of the chuck axis of each tool parallel to itself within a given area so as to make possible operations which are displaced with respect to the workpiece-holding disc, there is provided a device for positioning the chuck axis, said device being called "polar coordinates device" and being illustrated in FIGS. 22 and 23.

30 The small block 72 guiding the chuck 99 is provided with two bushes 73, 74 with parallel axes eccentrically disposed with respect to each other.

35 The chuck 99 of the motor 98 slides on balls in the eccentric hole of the bush 74. The eccentric bushes may be rotated, i.e. angularly displaced by means of the gear control 75, 76. The axis of the chuck may thus occupy every possible position within the circumference 77.

40 FIG. 24 relates to a device which could be called "cartesian coordinates station" and which may be applied to each chuck for the displacement thereof according to two coordinate axes, a vertical and an 45 horizontal one, whereby the control is effected by means of the peripheral cams 8 (FIG. 1).

45 The chuck 99 (FIG. 24) is fixed to the frame 130 and may slide horizontally along the guides 131.

50 The control of the horizontal displacement occurs by 55 means of one of the cams of the group 8 which acts on the roller 133 by actuating the lever 132. All the block formed by the frame 130, by the guides 131 and the plates 134 slides along the columns 135 thereby allowing for the vertical displacement. The control of the 60 vertical displacement also occurs by means of another cam of the group 8 acting by way of the lever 136.

55 It is obvious that by suitably combining the movement of the two cams of the group 8 for the horizontal and vertical displacement it is possible to impart to the chuck 99 any required movement thereby to profile and shape work-pieces with any possible, even very complex form.

It is furthermore possible to combine the above mentioned movement with the horizontal movement of the chuck for forming special curved surfaces.

FIGS. 25, 26, 27 relate to a device which could be denominated "orbital station" device. This device enables the tool to effect circular movements.

The chuck 99 (FIG. 25) is guided in the eccentric hole 136" (FIG. 26) provided in the bush 136 and carrying on its periphery a toothing 136'. These teeth are in contact with the toothed wheel 137 actuated by the shaft 141 (FIG. 27) fixed to the toothed wheel 138 actuated by the rack 139.

The rack is, in its turn, set into motion by the lever 140 actuated by way of the tappet by one of the cams of the group 8 (FIG. 1).

Simultaneously with to the circular motion imparted by the above mentioned devices, the chuck may undergo a vertical displacement imparted thereto by means of the lever 142 (FIG. 25) which, in its turn, is actuated by one of the cams of the axial group 95 (FIG. 1).

FIGS. 28 and 29 relate to devices serving to feed the raw material in the form of a wire or bar, said wire or bar having a circular or polygonal section or any other section which may be suitable for the operation in question.

The feeding operation (as illustrated in FIG. 28) is carried out vertically and is used for those workpieces the working on which requires fixing them in the gripper in vertical position.

The material which is in the form of a wire roll is introduced vertically into the feeding device and is straightened (before passing to the self-centering gripper of the chuck) by a rotating straightener illustrated in FIG. 27 or by a roller straightener of conventional type.

The frame 145 of the wire straightener is set into motion by the central shaft 5 (see also FIG. 1) by means of the gear 147. The wire passes through the bushes 148, the central one 148' being eccentric with respect to the axis. The eccentricity may be modified according to the diameter and the tape of material to be straightened.

The wire straightener simultaneously performs a vertical displacement controlled by the cam 149 by way of the rod 150 and the lever 151.

The wire is fed intermittently.

During this intermittent feeding motion of the wire, the wire straightener moves with a speed which is lower than that of the wire itself and, once the feed of the wire has come to an end, the wire-straightener, still rotating, moves backwards in a vertical direction. The wire is thus straightened during the whole working period and not only during the relatively short time it moves forward.

It is obvious that the vertical movement of the wire straightener is coordinated with respect to the wire feed so as to maintain approximately constant the relative speed of the wire and of the wire straightener. The intermittent feed of the wire is effected by means of the lever 52 actuated by way of the tappet by one of the cams of the group 8 (FIG. 1). The lever 152 actuates the toggle 153 which acts on the piston 154. This piston comprises the jaws 155 which, by way of the pawls 156, clamp the wire during its feeding phase.

The pivot 157 limits the travel of the toggle 153. The lever 152 keeps on travelling and imparts to the piston 161 a vertical displacement by means of the toggle 162. Thus the end of the piston 161 comes to press on the intermediate body of the gripper 163, thereby closing said gripper. At the end of this operation the piston 161, through the toggle 162, 153, returns to its starting position.

10 The auxiliary chuck 158 with its milling tool 159 is displaced by means of a cam of the group (8) (FIG. 1) upward to cut said wire.

15 The piston 160 acts as a ledge and defines thereby the exact length of the wire introduced into the gripper 163 of the plate 17 carried by the rotating turntable 16 (see also FIG. 1).

The piston 164 controlled by the lever 165 acts as a reaction or opposition part to the gripper closing device, i.e. serves to discharge the force imparted to the rotating turntable 16 when the piston 161 closes the gripper.

20 FIGS. 29 and 30 relate to a device for the horizontal feeding of the wire, i.e. to a device which is used in connection with pieces, the working of which requires the fixing of the workpieces in the associated gripper in horizontal position. The material, i.e. the raw wire or the bar, before being introduced into the self-centering gripper of the chuck is straightened (or merely guided) by means of a rotating device such as the one illustrated in FIG. 28 or by two groups of straightening rollers: a horizontal group 166 and a vertical group 166'.

25 The center to center distance between the rollers is adjustable so as to adapt to the various materials and to enable roller-leveling the wire in the direction of the two axes of the rollers, whereby the wire is perfectly straightened. The wire is fed by means of the slide 167 having the two levers 168, 168' pivoted thereon and acted upon by the springs 169, 169'.

30 The slide is operated by means of the lever (170) and the tappet 171. During the displacement of the slide in the sense of the arrow, the levers 168, 168' block or clamp the wire so that the wire moves forward together with the slide. During the return travel of the slide, the wire is released or free. Once the feed movement of the wire has come to an end, the pliers closes similarly to what happens with the device illustrated in FIG. 28. Successively the chuck 172 with the milling tool 173 is lowered by means of the tappet 174 so that the wire 35 may be cut.

35 FIGS. 31 and 32 relate to a device enabling one to center in the self-centering pliers of the chucks the stamped, pre-turned, punched or otherwise pre-shaped raw pieces or blanks. In this case the device is an actual universal charging-discharging device with a gripper-closing and opening system.

40 It comprises, as illustrated in FIG. 31, a piston 176 operated in a vertical direction by the lever 177 which is driven or controlled, in its turn, by a cam of the axial group 95 (FIG. 1). The same piston 176 receives a rotary movement about its axis by means of the rack 178 and of the toothed wheel 179. The rack 178 is operated by one of the cams of the group 95. The piston 176 carries at its lower end a square angle element 180, the ends of which have pivoted thereon two pairs of jaws 181, 181' (FIG. 32). These jaws are held closed elastically by springs 182, 182' and may be opened by the

rod 183 provided with a conical portion 183' (FIG. 31) and coaxial to the piston 176.

The piston 176 is lowered and, at the same time, the rod 183, driven by the mechanism 184 and the tappet 185 actuated by the cam 200, opens the jaws 181, 181'. 5

The jaws 181' are brought near the finished piece 187, clamped by the relative self-centering gripper 169, while the jaws 181 are brought near the blank 186.

Moving away, the rod 183 successively enables the jaws 181, 181' to grip the finished piece 187 as well as 10 respectively the blank 186.

The self-centering gripper 169 is then opened, the jaws 181' lifted and then rotated 90°.

The piston 176 is then lowered again. The blank 186 is thus brought to be coaxial with the gripper 169 while the finished piece 187 is now outside the rotating turntable 16 (FIG. 1). The rod 183 opens again the jaws 181, 181' thereby releasing the two pieces. The gripper 169 is then closed while the piston 176 with its associated block 180 and the jaws 181, 181' is returned to its starting position. 15

What is claimed is:

1. A machine for high speed, extremely precise mass production of pieces having small dimensions and complex forms, characterized:

by a turntable (16) stepwise rotating about a central shaft (5) and provided with a plurality of discs (17) carrying the workpieces, said discs being distributed at equally spaced angular intervals along the periphery of said turntable, each interval corresponding to a station in which a certain work operation is carried out, the different work operations being effected simultaneously on different workpieces; coaxially and externally to said central shaft (5) there being disposed in succession from the inside to the outside; an inner stationary sleeve (194), an intermediate bush (18) rotating with said turntable (16) and an outer stationary frame (193); 20

by main members to intermittently move said turntable to pass from one work station to the next one in the shortest possible time;

by tool-holding chucks situated in each work station and disposed above, at the side and under the periphery of the turntable in correspondence to each workpiece, said chucks having their working movement imparted thereto by groups of peripheral cams (8) disposed at the periphery of the turntable between one station and the other as well as by a group of axial cams (95) disposed along the axis of the turntable, with possibility of simultaneously working the pieces with at least three chucks for each workpiece-carrying disc, said chucks having their axes differently disposed and orientable as a whole through an angle of about 200° and fixable to the outer stationary frame (193) coaxial to the central shaft (5); 25

by means to exactly fix with great rigidity the position reach by the turntable at each work station before starting the work operation, said fixing being obtained by engaging and firmly holding said stationary inner sleeve (194) as well as said external stationary frame 30

by secondary members to displace angularly to itself the axis of each workpiece-carrying disc so as to

bring the same into the right working position and means to fix the same in the exact position before starting the work operation; said discs being shaped for working with chucks placed below and above the same.

2. The machine as claimed in claim 1, characterized in that said main members to intermittently move said turntable to pass from one station to the next one comprise a main motor (3) driving, by means of a speed variator, a worm wheel (4) and therewith the main shaft (5) coaxial and idle with respect to said turntable (16), said central shaft (5) carrying, fixed coaxially thereto, a secondary turntable (9) profiled as a cam (19) so as to operate, with intermittent accelerated and decelerated motion and through a lever system (21, 22, 23), a central oscillating lever (24) which is also coaxially and idly mounted on said central shaft (5), said central oscillating lever (24) carrying, in its turn, an engaging member (25) provided with complementary means (18') situated at the base of the intermediate rotating bush (18) coaxially fixed to the above mentioned turntable (16); the engaging and disengaging of said members (18', 25) being controlled by a double acting cam (26) fixed to the central shaft (5); said double acting cam being profiled so as to enable, during the angular displacement phase of the central oscillating lever (24), the engagement with the intermediate rotating bush (18) and therefore with the turntable (16) during rotation thereof and the disengagement therefrom during the return phase of said oscillating central lever (24). 35

3. The machine as claimed in claim 1, characterized in that said system of levers (21, 22, 23) actuate said central oscillating lever (24) over a click-joint comprising a fork member (23') situated at the end of the lever (23) directly connected to the central oscillating lever (24), said fork member 23' having a slide member (191) sliding thereon, pivoted to the preceding lever (22) and fixed to a bush (193) having an annular groove (193') containing balls (194') situated in holes in a body (195) coaxially placed outside of said bush (193), said body being axially subjected to stresses by a spring (196); the whole being so designed and constructed that during the normal functioning of the machine the joint behaves as a rigid connection while, in case of excessive stresses required to angularly displace the rotating platform (16), the action of said spring is overcome, the balls come out of said annular groove (193') thereby releasing the bush (193) from the body (195) preventing stress from being transmitted to the central oscillating lever (24) which, in its turn, is connected to the members driving the rotating turntable (16) by way of a damping device (198). 45

4. The machine as claimed in claim 1, characterized in that said engagement member (25) is made to slide within a container (46) and is subjected to elastic stresses by springs (49); said engagement member (25) and said container comprising there-between the seat for a ball (48) adapted, under normal working conditions, to rigidly connect said two members and, under an axial stress higher than normal, to move radially so as to permit a reciprocal axial sliding motion. 50

5. The machine as claimed in claim 4, characterized in that one or the other of said complementary engagement members (19', 25') are cushioned. 65

6. The machine as claimed in claim 1, characterized in that to prevent the machine members from breaking in case of incorrect functioning of the machine, tappets acting on said peripheral cams (8) and on said axial cams (95) are provided with damping or cushioning devices, each constituted by two coaxial parts sliding one in the other (41, 42), one part (41) consisting of a hollow cylinder provided with a ball (40), the other part consisting of a coaxial stem (42) provided with a groove (42') having entering therein said ball pushed by a sleeve (44) subjected to elastic stresses by a spring (43), the whole being so designed that under an excessive stress the ball enters into the recess thereby enabling the stem (42) to slide into the hollow cylinder (41).

7. The machine as claimed in claim 1, characterized in that the secondary members to angularly displace the axis of each disc (17) so as to bring same into the right working position are constituted by a toothed wheel (32) fixed coaxially under each disc and by a toothed segment (33) coaxial with the central shaft (5) of the machine and fixed to the base frame; said toothed segment (33) having at regular intervals, between one work station and the next one, at least a tooth (33') which is lower than the others so as to permit the angular displacement of the disc driven by the turntable (16) without any of its own rotation, whereby the angular displacement of the disc passing from one working station to the next one may be varied by varying the number of teeth of the toothed segment (33) with respect to the number of teeth of the above mentioned toothed wheel (32).

8. The machine as claimed in claim 1, characterized in that the position of the turntable (16) and the one of the workpieces-carrying discs (17) is fixed in correspondence to each working station by means of blocking rods (14, 15) carried by a disc (13) actuated by a double acting cam (10) fixed to a secondary turntable (9) fixed to the central shaft (5); said blocking rods passing through holes in the stationary part of the machine and holes in the step wise rotating turntable (16).

9. The machine as claimed in claim 1, characterized in that the groups of peripheral cams (8) and the group of axial cams (95) are operated by a pair of bevel gears (7), the pair fixed to the central shaft (5) having a number of teeth which is a multiple of the one driving the peripheral cams (8) according to the number of work stations so as to readily permit the phase setting of the machine.

10. The machine as claimed in claim 1, characterized by members to facilitate the acceleration and the deceleration of the rotating turntable (16) comprising: a first electromagnetic coupling (28) by way of which the central shaft (5) is actuated by the main motor (3) over a speed variator; a second electro-magnetic coupling (30) by way of which the central shaft (5) is driven by an auxiliary motor (31) having a speed (n_2) which is different from that of the main motor (n_1) while an additional coupling (29) serves to stop the central shaft (5) in case of an emergency; the connection of said electromagnetic coupling being controlled by a contactor through the group of peripheral cams (8).

11. The machine as claimed in claim 1, characterized by members to control the rotating turntable (16) with two different speeds which are adjustable by means of a direct current motor the speed of which is electronically controlled a generator-tachometer (53) generating an electric potential which is directly proportional to the number of revolution of the motor, the rotary speeds of the rotating turntable being preselected by means of two potentiometers (54, 55) while a commutator (63) driven by one of the lateral cams (8) inserts one or the other of the preselected speeds; a braking circuit, in which the motor is used as a generator, for the rapid change from one speed to the other, while an electromagnetic brake is provided for emergency stopping.

12. The machine as claimed in claim 1, characterized by a mechanical device to facilitate the acceleration and deceleration of the rotating turntable (16) by increasing the displacement speed thereof from one work station to the next one, said device being characterized by an inner body (194) fixed to the central shaft (5) and having radial holes with pistons (101) sliding therein, said pistons being stressed outwards by springs (102), and having fixed thereto rollers (104) which slide along concave surfaces (105) provided in the cylinder (18) in a number equal to that of the work stations of the turntable (16), said concave surfaces being disposed in such a way that, when the turntable stands still during the work operation, the rollers (104) are in the highest region of said concave surfaces while, during the displacement phase of the turntable, they are in the lateral or central region of said concave surfaces.

13. The machine as claimed in claim 1, characterized by rocker arm devices to control the displacement of each tool-carrying chuck; each device comprising a lever (117) actuated by a tappet (116) receiving the motion from a control cam (8), said lever (117) acting on a pivot (118) to transmit the motion by way of a profiled pawl (70) to two coaxial and polygonal lateral bushes (71, 71') one of said bushes actuating a lateral arm (94), the other actuating another lateral arm (94') each placed at one side of a chuck-actuating motor (98); said pawl being so profiled as to have two grooves (70', 70'') defining a central protruding portion acted upon by the driving force whereby the same is distributed in balanced manner on each of said two arms, placed at one side of the motor.

14. The machine as claimed in claim 1, characterized by devices to displace the axis of each chuck parallel to itself within a given area for to work pieces with complicated forms, each device comprising two bushes with parallel axes (73, 74) eccentrically disposed one within the other and angularly displaceable by means of a gear control unit (75, 76); the inner bush being adapted to receive axially slidable therein on balls the motor (98) carrying the corresponding chuck.

15. The machine as claimed in claim 1, characterized by devices applicable to the various chucks to permit the displacement thereof along two axes, a vertical and a horizontal one, each device comprising a frame (130) having fixed thereto the preselected chuck (99), said frame being slidable along horizontal guides (131) with the control coming from one of the peripheral cams (8) by way of a roller (133) and a lever (132); the combination of members forming the frame (130) and the

guide (131) being adapted to slide vertically along vertical guiding columns by means of a second cam of the peripheral group (8) and of a central lever (136); said frame (130) being adapted to be fixed to the vertical columns (135) by means of a gauge member when its displacement along the coordinate axes is not required.

16. The machine as claimed in claim 1, characterized by devices enabling the various tools to effect circular motions, each device comprising a bush (136) with an eccentric guiding hole (136'') for the corresponding chuck (98); said bush (136) being provided at its periphery with a toothed wheel (136') engaging a complementary toothed (137) of a wheel actuated by way of a shaft (141) by a second toothed wheel (138) which is driven by a rack (139) set into motion by a lever (140) driven by way of a tappet by one of the cams of the peripheral group (8) (FIG. 1); whereby said chuck (98) may also effect contemporaneously a vertical displacement by way of a second lever (142) actuated by one of the cams of the axial group (95).

17. The machine as claimed in claim 1, characterized by a device feeding and straightening raw wire coming from a supply of wire, said device comprising a frame (145) set into rotation by the main shaft (5) of the machine; said frame carrying at least three bushes (148), the central one of which is eccentric with respect to the two others and also with respect to the rotational axis, the eccentricity being variable according to the diameter of the wire and the type of material; said frame being adapted to perform simultaneously also an intermittent axial displacement controlled by a cam (149) by means of a rod (150) and a lever (151), the wire being fed axially with a speed which is larger than that of the axial displacement of the above mentioned frame so that the wire is straightened also during the axial return motion of said frame.

18. The machine as claimed in claim 1, characterized by a device for horizontally feeding wire comprising a slide (167) having two levers (168, 168') pivoted thereon and pushed by two springs (169, 169'), said levers firmly holding the previously straightened wire during the forward travel of the slide and releasing said wire during the return travel of the same; said slide being driven by way of a lever (170) by a tappet-cam (171); a milling tool (173) also actuated by way of a tappet-cam (174) cutting the wire once the same has been introduced into the corresponding self-centering gripper.

19. The machine as claimed in claim 1, characterized by a device to introduce in the chucks pressed, pre-turned, stamped or otherwise pre-profiled raw pieces or blanks, said device comprising a piston (176) axially driven by a lever (177) actuated by a cam of the axial group, a rotary motion about its axis being imparted to said piston by way of a toothed wheel (179) and a rack (178) actuated by a second cam of the axial group (95), said piston carrying at its lower end a square shaped member (180), the ends of which have pivoted thereto two pairs of jaws (181, 181') held in closed position by springs (182, 182'), whereby said jaws may be opened by a rod (183) with a conical lower end portion (183') coaxial to said piston (176) and driven by a mechanism (184) with a cam (200) and a tappet (185); a pair of said jaws serving to clamp the finished piece (187) and the other clamp a blank (186); the lifting and successive rotation through 90° of said square shape member (180), after the finished piece has been disengaged from the corresponding self-centering gripper (169), permitting the discharge of the finished piece and the introduction of a new blank in said self-centering gripper (179).
